(57) **CLAIM**

The ornamental design for a front panel for a computer enclosure, as shown and described.

DESCRIPTION

FIG. 1 is a perspective view of the front panel for a computer enclosure with the pivoting doors in a closed position, viewed from a position to the right of the front panel. The remainder of the computer enclosure is shown in phantom line.

FIG. 2 is an elevation view of the front panel for a computer enclosure, with the pivoting doors in a closed position.

FIG. 3 is a left side elevation view of the front panel for a computer enclosure, with the pivoting doors in a closed position. The remainder of the computer enclosure is shown in phantom line.

FIG. 4 is a right side elevation view of the front panel for a computer enclosure, with the pivoting doors in a closed position. The remainder of the computer enclosure is shown in phantom line.

FIG. 5 is a top view of the front panel for a computer enclosure, with the pivoting doors in a closed position. The remainder of the computer enclosure is shown in phantom line; and,

FIG. 6 is a perspective view of the front panel for a computer enclosure with the pivoting doors in an open position, viewed from a position to the right of the front panel. The remainder of the computer enclosure is shown in phantom line.
